SWIVEL CONNECTOR FOR ELECTRIC
CABLES, CORDS, OR THE LIKE

Mario Larrabure S., Lima, Peru

Application October 29, 1943, Serial No. 508,146

2 Claims. (Cl. 173—324)

1

The invention relates to an electric connector and more especially to a swivel connector for electric cables, cords or the like.

The primary object of the invention is the provision of a connector of this character wherein the same is associated with an electric cable, cord or the like, particularly those serving as electric leads for electric lamps, irons, vacuum cleaners, telephone sets or any other electrically operated equipment, so that the wearing of the cable, cord or the like resultant from twisting thereof can be entirely avoided and in this way eliminating short circuits as is common in electrical devices which must often be handled without regard to the twisted condition of the cable, cord or the like.

Another object of the invention is the provision of a connector of this character wherein the construction thereof is novel in its entirety and its parts are readily accessible so as to correct any irregularity in the working thereof and for replacement of worn parts.

A further object of the invention is the provision of a connector of this character which is simple in its construction, thoroughly reliable and effective in operation, readily adaptable to electric cables, cords or the like as employed in electrical devices for the working thereof and also inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention and pointed out in the claims hereunto appended.

In the accompanying drawings:

Figure 1 is a perspective view of a combined telephone transmitter and receiver showing in elevation the connector constructed in accordance with the invention associated therewith.

Figure 2 is an enlarged elevation of said connector.

Figure 3 is a plan view of the same.

Figure 4 is a view in plan reversed to that of Figure 3 and partly broken away.

Figure 5 is an enlarged vertical sectional view through the connector.

Figure 6 is an elevation of certain working parts of the connector.

Figure 7 is an enlarged fragmentary sectional view with parts in elevation showing in detail one of the electric wire assemblies of the device.

2

Figure 8 is an exploded side elevation of companion follower pieces employed in the device.

Similar reference characters indicate corresponding parts throughout the several views in the drawings.

Referring to the drawings in detail, particularly Figure 1, A designates generally a combined receiver and transmitter of a telephone set, it being illustrated merely for disclosing the manner of use of the swivel connector B constituting the present invention and hereinafter fully described. It is to be understood that the swivel connector B can be employed with electric cords for other electrical devices, such as electric vacuum cleaners, electric irons, as well as with the detachable electric plugs generally associated therewith.

The connector B comprises a main body 10 preferably made from "Bakelite" and has a permanently closed end 11 for a central socket or bore 12 which opens through the opposite end of said body 10. This body 10 having the open end for the bore or socket 12 has rotatably fitted thereon a turning head 13 it containing a ball raceway 14 for bearing balls 15 which contact with the rim portion 16 of the body 10 so that rotary movement of the head 13 with smoothness and with minimum friction will be had relative to the body 10 for the swivel activity of the connector. This head 13 as shown in Figure 1 of the drawings is disposed next to the combined receiver and transmitter A at the point disclosed. It is preferable that the head 13 be insulated in any suitable manner and is concentrically disposed about an electric connection involving a central current conductor 17, an intermediate current conductor 18 and an outer current conductor 19, the conductor 17 being in the form of a rod while the conductors 18 and 19 are of tubiform. These conductors are suitably insulated from each other by insulating coverings 20. The conductors 17, 18 and 19 in their grouped relation to each other are extended into the socket or bore 12 in the body 10, as is clearly shown in Figure 5 of the drawings. The outer conductor 19 is insulated from the head 13 which is preferably made from insulating material, although it may be otherwise constructed for insulating purposes. These conductors 17, 18 and 19, through terminal parts 21 are electrically associated with the said combined receiver and transmitter A interiorly thereof.

Fixed to the conductors 17, 18 and 19 are grooved rollers 22, 23 and 24, respectively, the 55 grooves 25 therein form trackways for ball con-

tacts 26 which are held in engagement through companion followers 27 and 28 respectively having therebetween coiled expansion springs 29, the opposite ends of the latter affording current supply to the conductors 17, 18 and 19 from the electric wires 30 of an electric cable, cord or the like 31, these wires being carried through a tubular loop member 32 and are branched at 33, 34 and 35, respectively so that current supply will be unbroken from the said cable 31 to the conductors 17, 18 and 19, respectively.

It should be apparent that in the use of the connector as heretofore described there is no possibility of the twisting of the cable, cord or the like 31 in the handling of the combined receiver and transmitter or other electrical device or appliance, as the said body 10 is readily turnable with relation to the conductors 17, 18 and 19 in that the body 10 rotatably fits the head 13 therefor.

The loop 32 is anchored about the body 10 exteriorly thereof by a circular band 36 and such loop 32 is swingingly associated with this band to permit tilting of the connector in the use thereof and the electrical device with which it is associated.

It is preferable to have the followers 27 and 28 as well as the spring 29 therebetween confined within tubular casings 37 properly fitted within the body 10.

It is also to be understood that the cable, cord or the like 31 is of the usual or common insulator sheathing type.

What is claimed is:

1. A swivel connector for electric conductors for use with an electric appliance comprising a hollow insulating cylinder closed at one end, resiliently secured ball contacts in the cylinder extending into the open center thereof, concentric conductors insulated from each other and in the hollow cylinder and forming a rotatable assembly secured in fixed relation to the appliance, grooved contact rollers fixed on the upper ends of the conductors engaging the respective ball contacts, a swivel head rotatably secured on and enclosing the open end of the cylinder and secured in supporting relation to the said assembly whereby the cylinder and contacts will be movable relative to the head and assembly.

2. A swivel connector for electric conductors for use with an electric appliance comprising a hollow insulating cylinder closed at one end, resiliently secured ball contacts in the cylinder extending into the open center thereof, concentric conductors including a central rod and spaced insulated tubes terminating successively short of the adjacent inner conductor forming a rotatable assembly secured in fixed relation to the appliance and in the hollow cylinder, grooved contact rollers on the upper stepped ends of the conductors of the assembly engaging the respective ball contacts, a swivel head rotatably secured to and enclosing the open end of the cylinder and secured in supporting relation to the said assembly whereby the cylinder and contacts will be movable relative to the head and assembly.

MARIO LARRABURE S.
